ARTIFICIAL FIREPLACE

Kenneth C. Haas, Eggertsville, N. Y.

Application July 23, 1951, Serial No. 15,991

Term of patent 7 years

(Cl. D81—7)

To all whom it may concern:

Be it known that I, Kenneth C. Haas, a citizen of the United States, residing at Eggertsville, in the county of Erie and State of New York, have invented a new, original, and ornamental Design for an Artificial Fireplace, of which the following is a specification, reference being had to the accompanying drawing, forming a part thereof.

Figure 1 is a perspective view of the artificial fireplace embodying my new design. Figure 2 is a front view of the same. Figure 3 is a top plan view of the same on a reduced scale.

I claim:

The ornamental design for an artificial fireplace, substantially as shown.

KENNETH C. HAAS.
